[57] CLAIM

The ornamental design for a furniture deck edging, as shown and described.

DESCRIPTION

FIG. 1 is a top plan view of a length of furniture deck edging embodying my design, with its central portion broken away to indicate indeterminate length,

FIG. 2 is a rear elevational view of the edging as shown in FIG. 1,

FIG. 3 is an inverted plan view of the edging as shown in FIG. 1,

FIG. 4 is a front elevational view of the edging as shown in FIG. 1, and

FIG. 5 is an enlarged right end view of the edging as shown in FIG. 1.

The edging is of uniform cross-sectional contour throughout its length.
